PRESSURE REGULATOR

George M. Deming, Orange, N. J., assignor to Air Reduction Company, Incorporated, New York, N. Y., a corporation of New York

Application May 20, 1942, Serial No. 443,719

7 Claims. (Cl. 128—142)

This invention relates to pressure regulators such as are used for oxygen therapy, and by aviators for breathing at high altitudes. The invention relates especially to apparatus for supplying a mixture of gas and air.

In its broadest aspects it is an object of the invention to provide an improved pressure regulator for supplying gas to a breathing mask, or for other purposes where it is desirable to prevent changes in the force required to operate the valve of the regulator.

It is an object of the invention to provide improved breathing apparatus in which the ratio of oxygen and air is determined by the relative opening of the respective supply passages.

In one type of oxygen breathing device a mask is provided with an air inlet through which air may be drawn into the mask with each inspiration of the wearer. The mask has also a diaphragm that controls a valve for admitting gas, such as oxygen, to the mask. The oxygen-air ratio is controlled by partially obstructing, in varying amounts, the air inlet passage, often by aneroid control in aviation breathing masks, but usually by manual setting in masks for oxygen therapy or anesthesia. It is another object of the invention to stabilize the operation of the gas-inlet valve of such masks and to obtain an air-gas ratio that is substantially independent of the demand rate (i. e., rate of flow).

The oxygen supply valve is subject on one side to the pressure in the mask and on the other side to the pressure in the supply line. This invention prevents the pressure differential across the valve from changing sufficiently with the rate of flow to impair the operation of the breathing apparatus.

This application is a continuation-in-part of my application Serial No. 386,618, filed April 3, 1941.

Other objects, features and advantages of the invention will appear or be pointed out as the specification proceeds.

In the accompanying drawing, forming a part hereof:

Fig. 1 is a fragmentary sectional view through a mask and regulator embodying this invention.

Fig. 2 is a detail view of the air inlet valve for regulating the degree of opening of the air inlet passage shown in Fig. 1.

Fig. 3 is a sectional view, on a reduced scale, taken on the line 3—3 of Fig. 1, but with the gas valve in open position.

Fig. 4 is a graph showing the performance of this invention compared with devices of the prior art.

A face mask 10 includes a metal shield 11 with a cushion 12 attached around the edge of the shield for contact with the face of the wearer. The mask is connected with a source of oxygen by a soft rubber hose 14 that fits over a nipple 15 at the bottom of the mask.

The interior of the mask communicates with the surrounding atmosphere through an air port 17 that opens through the side of the mask. The extent of opening of the air port 17 is controlled by a valve that comprises a plate 18 movable transversely of the air port 17 and about a screw 19 as a pivot. The valve plate 18 has an edge that moves along a scale 20 (Fig. 2) which indicates the concentration of oxygen that the wearer of the mask will receive for any position of the plate 18 as it is moved over the air port 17. The screw 19 can be tightened to hold the valve plate 18 in any selected position along the scale 20.

For an aviation breathing mask the air port 17 is left fully open at sea level and closed progressively further as the altitude increases until at some altitude the air port is completely closed and the aviator breathes pure oxygen.

The mask comprises the reduced-pressure chamber of a pressure regulator of the inverse type that controls the supply of oxygen. A regulating spring 23 presses against a bearing disk 24, which may be made of paper and secured to the front of a diaphragm 25. The edge of the diaphragm 25 is clamped between the metal shield 11 and a front cover 26 that is fastened to the shield by screws 27. There are openings 28 in the cover 26 for exposing the front of the diaphragm 25 to the pressure of the surrounding atmosphere.

A regulating valve lever 30 is connected to the mask by means of two loosely fitting fulcrum pins 31 and has a head 32 against the back of the diaphragm 25. Hence, any inward thrust upon the diaphragm 25 and the head 32 of the regulating lever 30 results in a downward thrust of a toe 34 of the lever 35. This downward thrust is communicated to a valve 36 through a thrust pin 37 which slides freely in a drilling in a wall 38.

The valve 36 controls passage of gas through a port 40. The thrust pin 37 is in axial alignment with the port 40 and the lower end of this thrust pin 37 fits into a central socket in the top face of the valve 36. The fit of the thrust pin 37 in the socket of the valve 36 is loose enough to permit the valve to rock slightly on the end of the thrust pin and thus insure tight closure of the valve 36 when the diaphragm 25 moves and the valve 36 is forced upward by the pressure of the gas beneath it.

The valve 36 has a face that is flat and smooth, and is preferably made of material that requires very little compression to effect a gas-tight closure. Soft rubber is suitable if of a grade that is sufficiently flat and smooth, though metal can be used. The lip against which the valve 36 seats is metal.

When the apparatus is not in use and there is no gas pressure under the valve 36, the spring 23, acting through the lever 30 and thrust pin 31, pushes the valve 36 as wide open as possible, but the maximum opening of this valve 36 is limited by a stop 42. I have found that the pressure of oxygen in the mask can be made independent of the demand rate by restricting the flow of the gas to the port 40. The flow is restricted by limiting the lateral or peripheral clearance between the valve 36 and the surrounding wall 44. The pressure on the downstream side of the valve 36 gradually increases with increasing rates of discharge, that is, with increasing displacements of the valve 36 from the lip against which the valve 36 seats at the end of the port 40.

The regulating spring 23 is preferably made sufficiently weak so that oxygen flows into the mask when the pressure in the mask is slightly less than that of the surrounding atmosphere, for example at a pressure of about .05 of an inch of water below that of the surrounding atmosphere. As long as the pressure within the mask is above that level, no oxygen will be discharged to the mask. Hence, as long as air can be inspired through the air inlet port 17 without creating a pressure differential greater than .05 of an inch of water, no oxygen is supplied to the mask. If, however, the valve plate 18 covers part of the air inlet 17, there are periods in each respiratory cycle when more or less oxygen flows into the mask.

To permit adequate exhaust of exhaled air from the mask when the valve 18 is partly or completely closed, the mask is equipped with an exhaust valve 45 that covers an exhaust port in the side of the mask. The valve 45 is lightly loaded by a spring.

The pressure drop through the port 40 is a function of the rate of flow of the oxygen. As the rate of flow increases, the pressure drop through the port 40 increases. In an ordinary regulator of the inverse type the pressure at the valve-end of the port 40 would increase, and this would make the pressure differential on the opposite sides of the valve 36 less, so that less thrust would be required on the pin 38 to open the valve 36 wider. Such a condition causes instability of the regulator. When the air port 17 is open or partly open, any variation in the amount of suction in the mask required to operate the oxygen supply valve 36 will change the proportion of air and oxygen that that amount of suction draws into the mask.

The dotted line 46 of the graph shown in Fig. 4 represents the variation in the amount of suction in the face mask that would be required to move the valve 36 toward open position if the gas passage around the sides of the valve 36 were of such large cross-section that there would be little pressure drop in the gas passing around the valve. As the rate of flow increases and the suction required to open the valve decreases, it is apparent that a larger portion of oxygen and relatively less air will enter the mask when the wearer inhales.

The reduced cross-section of the gas passage between the wall 44 and the side of the valve 36 causes a pressure drop in the passage around the valve, and this drop is proportional to the rate of flow and increases the pressure differential be-

tween the back of the valve 36 and that part of the front of the valve that extends radially beyond the valve seat. The valve seat comprises a raised lip, and the valve 36 has a substantial radial extent beyond the valve seat. The pressure drop in the annular passage between the wall 44 and the valve 36, therefore, counteracts the effect of the pressure change at the upstream end of the port 40.

If the gas passage around the sides of the valve 36 is sufficiently restricted, the pressure differential on opposite sides of the valve 36 will remain constant with variations in the rate of flow, and the suction to open the valve 36 under such conditions is represented by the line 47 in Fig. 4. Too much restriction of the gas passage around the valve 36 causes the line 47 to curve upward, with resulting increase in the proportion of air drawn into the mask.

If the port 40 has a diameter of .1495 inch (#25 drill) and the diameter of the valve 36 is .263 inch, the diameter of the gas passage around the valve 36 (i. e., at the wall 44) should be of the order of .344 inch in a regulator such as shown in the drawing. It should be noted that the effect of the raised valve seat is to cause a more abrupt change in the direction of the gas flow just before the gas enters the port 40. With the valve extending radially beyond the raised seat, this change in the direction of the gas flow results in some dynamic pressure head against a portion of the downstream face of the valve, and this pressure increases with the rate of flow and must be countered by added pressure drop in the passage around the valve. The cross-sectional area of the annular gas passage around the valve is of the order of two times the cross-sectional area of the port, with the relation of diameters indicated above. These specific values are given by way of illustration only, and not as limitations of the invention. This illustration is for a raised valve seat, such as shown in the drawing and commonly used in pressure regulators. The dynamic pressure effects vary with different valve seats.

Various changes and modifications of the invention can be made, and some features of the invention can be used without others.

I claim:

1. An aviation breathing mask having an oxygen inlet port and an air inlet port, and including a valve commanding the oxygen inlet port, said valve including a movable valve body and a seat for said valve body, another valve commanding the air inlet port, a device for changing the extent of opening of the air inlet valve with increase in altitude, a diaphragm forming a wall of the mask and movable in response to pressure changes within the mask, motion-transmitting connections between the diaphragm and the oxygen inlet valve body, and means for causing a substantially constant air-oxygen mixture to be drawn into the mask regardless of the demand rate, said means including a passage of restricted cross-section around the side of the movable body of the oxygen inlet valve, said cross-section being so correlated with the cross-section of the oxygen inlet port that it produces a pressure drop in the gas flowing around the valve body that approximately offsets the effect on the oxygen inlet valve body of the changes in the pressure drop through the oxygen inlet.

2. An aviation breathing mask that comprises the reduced-pressure chamber of a pressure regulator of the inverse type, said mask including an oxygen inlet port, a valve commanding

the oxygen inlet port, said valve including a movable valve body and a seat for said valve body a flexible diaphragm forming a wall of the mask and exposed on the outside to the pressure of the atmosphere surrounding the mask, motion-transmitting connections between the diaphragm and the valve including a lever operably connected with the diaphragm, adjustable valve means commanding an air inlet opening through a wall of the mask, and means for maintaining the pressure differential on opposite sides of the oxygen inlet valve body substantially constant for different displacements of said valve body, said means including a restricted oxygen passage upstream from the oxygen inlet port and around the valve body for causing an increase in the pressure drop of the gas flowing around the valve body as the rate of such flow increases, the cross-section of the restricted passage being so correlated with the cross-section of the oxygen inlet port that the increase in the pressure drop around the valve body approximately offsets the increased pressure on the downstream side of the valve body caused by the increased pressure drop through the oxygen inlet port.

3. A pressure regulator comprising a reduced-pressure chamber, a port through which oxygen enters the reduced-pressure chamber, a valve seat, a valve commanding the port and movable toward and from the seat in the direction of the axis of the port, and an oxygen passage around the sides of the valve, said passage having a cross-section correlated with the cross-section of the port so that at different rates of flow the pressure drop in the passage around the valve substantially offsets the effect on the valve of the pressure drop through the port.

4. A pressure regulator as called for by claim 3 in which the valve seat is raised to cause a change in the direction of gas flow and the cross-section of the passage around the valve is of the order of twice as great as the cross-section of the port.

5. In a pressure regulator of the inverse type in which gas flows into a reduced-pressure chamber through a port and a valve in a passage on the upstream side of the port closes in the direction of the gas flow and against a seat at the

upstream end of the port, the improvement which comprises a passage with a restricted cross-section around the valve for increasing the pressure drop of the gas flowing around the sides of the valve and to the seat as the rate of flow increases, said passage cross-section being so related to the cross-section of the port that the pressure drop around the valve substantially offsets the effect on the valve of the increased pressure at the upstream end of the port with increased rates of flow.

5 6. In a pressure regulator as described in claim 5, the further improvement which comprises a valve that extends radially for a substantial distance beyond the valve seat, and an annular lip at the upstream end of the oxygen inlet port, which lip serves as the valve seat.

10 7. An aviation breathing mask having an oxygen inlet port and an air inlet port, a valve commanding the oxygen inlet port, said valve including a movable valve body and a seat for said valve body, an adjustable valve commanding the air inlet port, a diaphragm forming a wall of the mask and movable in response to pressure changes within the mask, motion-transmitting connections between the diaphragm and the movable body of the oxygen valve, the oxygen inlet port at the downstream side of the movable body of the oxygen valve having a sufficient length in the direction of flow through the port to cause a pressure drop through it which increases with increasing displacements of said movable body and thus tends to increase the pressure on the downstream side of said movable body with increasing displacements thereof and means for causing a substantially constant air-oxygen mixture to be drawn into the mask regardless of the demand rate, said means including a passage of restricted cross-section around 20 the side of the movable body of the oxygen valve, said cross-section being so correlated with the cross-section of the oxygen inlet port that it produces a pressure drop in the gas flowing around the valve body that substantially prevents any increase in pressure on the downstream side of the movable body of the oxygen valve when its displacement is increased.

GEORGE M. DEMING.
